GRAVE MARKER

John M. Lucken and Richard R. Clemmer, St. Paul, Minn., assignors to Remembrance Memorial, Inc., Minneapolis, Minn., a corporation of Minnesota

Filed May 23, 1960, Ser. No. 60,705

Term of patent 14 years

(Cl. D79—2)

FIG. 1

FIG. 2

FIG. 3

FIG. 4

FIG. 5

FIG. 7

FIG. 1 is a top plan view of a grave marker, showing our new design;

FIG. 2 is a perspective view thereof showing the cover in a raised position;

FIG. 3 is a top plan view of another embodiment of the grave marker;

FIG. 4 is a perspective view of the grave marker of FIG. 3 showing the center cover portion in a raised position;

FIG. 5 is a top plan view of still another embodiment of the grave marker;

FIG. 6 is a perspective view of the grave marker of FIG. 5 with the cover in raised position; and

FIG. 7 is a side elevational view of the grave markers shown in FIGS. 1-6, inclusive, with the cover in closed position.

We claim:

The ornamental design for a grave marker, substantially as shown and described.
